HAIRPIN RECEPTACLE

Philip Napoleon Boudreau, Lake Megantic,
Quebec, CanadaApplication March 22, 1950, Serial No. 151,084
In Canada November 8, 1949

1 Claim. (Cl. 223—109)

1

This invention relates to a receptacle adapted to hold hairpins and like small articles used by ladies in doing their hair up, and the object of the invention is to so form the interior of a receptacle of this class whereby a pin to be removed therefrom will be elevated above its fellows while still in the receptacle so that the user may remove it with great ease from its fellows, with the fingers of one hand, thus leaving the other hand free to hold the hair in place until a hair pin, for example, is put to use, as hereinafter more particularly explained.

Figure 1 is a central longitudinal section through the receptacle, and Figure 2 is a plan view thereof.

Figure 3 is a vertical section on the line 3—3, Figure 1, and

Figure 4 is a vertical section on the line 4—4, Figure 1.

In the drawings like characters of reference refer to the same parts.

It is well known that such articles as hairpins, safety pins, and the ordinary dressmaker's pins, are not readily individually separated from their fellows for removal from receptacles having flat inner bottoms or floors, and vertical walls. It is to completely overcome the disadvantage in use of such well-known receptacles that the present receptacle has been designed.

The receptacle may have any desired exterior form, and although it is illustrated as having a lid, such is not essential, though it is preferably used. The type of lid shown is of course well known.

The exterior of the bottom 5, of the receptacle 2, is flat so that the receptacle will stably rest on a table or dresser, and although the front wall 9, of the receptacle is exteriorly shown as in the form of a surface 3', sloping inwardly, this shape is not essential.

The inner surfaces of the rear wall 3, and the side walls 4, are vertical with relation to the bottom 5. In the walls 4, are formed horizontal grooves 6, to receive the lid or cover 7.

The upper surface of the bottom 5, forms the floor 8, of the receptacle. This floor 8, is formed to slope longitudinally of the receptacle in two relatively long angularly-disposed surfaces from the rear wall 3, to the top of the front wall 9. These angularly-disposed surfaces are joined by a trench 10', extending from one side wall to the other as shown clearly in Figure 1, and for its whole length this floor is concave in form essentially from one side wall 4, to the other, as shown at 10. The deepest part of this concavity coincides with the longitudinal axis of the floor 8. The purpose of this concavity is to use the sloping sides thereof to cause the pins for the entire

2

length thereof to move into the deepest part of the concavity in parallel relationship where they can be always located in this relationship, one by one, by the fingers and readily drawn up the lower sloping surface of the floor and up the upper sloping surface thereof across the trench 10' onto and over the flat ledge 11, of the wall 9, and out of the box.

By means of the ledge 11, as the article being withdrawn is moved thereonto it assumes a horizontal position and part will extend therebeyond, leaving it free to be readily grasped by the hand.

The construction shown makes the inner sloping side of the wall 9, of the container, part of the concaved floor 8.

As a hairpin is drawn along the upper end of the lower sloping surface of the floor 8 it will, because of its length, span the trench 10', (see Fig. 1) with the result that the pin will be elevated above its fellows and thus be readily identified by the fingers and drawn upwardly on the rest of the floor to the flat edge 11.

Changes in shape of construction may be made in that shown without departing from the spirit 25 of the invention, and the scope of the claim.

I claim:

A receptacle for the purpose specified, having one interior vertical rear wall and two interior vertical side walls, and a front wall having a top flat ledge the floor of a receptacle sloping longitudinally of the receptacle in two angularly-disposed relatively-long surfaces extending from said rear wall to the top flat ledge of the front wall of the receptacle, the said surfaces being formed with a concaved channel, the longitudinal centre of which coincides with the longitudinal axis of said receptacle and joined by a trench defined by the surfaces immediately adjacent either side of the point of intersection of the two angularly-disposed relatively-long surfaces whereby as a pin is moved from the lower surface to the upper one it will span said trench and thus be elevated above its fellows and thus facilitate its removal from the receptacle by the 45 fingers.

PHILIP NAPOLEON BOUDREAU.
